UNITED STATES PATENT OFFICE.

WILLIAM LOWMAN, OF SILVER CREEK, NEBRASKA, ASSIGNOR OF ONE-HALF TO
ERNEST P. DUSSELL, OF COLUMBUS, NEBRASKA.

GAS-IGNITING SYSTEM.

1,189,370.

Specification of Letters Patent.

Patented July 4, 1916.

Application filed July 19, 1915. Serial No. 40,748.

To all whom it may concern:

Be it known that I, WILLIAM LOWMAN, a citizen of the United States, residing at Silver Creek, in the county of Merrick and State of Nebraska, have invented certain new and useful Improvements in Gas-Igniting Systems; and I do declare the following to be a full, clear, and exact description of the invention, such as will enable others skilled in the art to which it appertains to make and use the same.

My invention relates to improvements in gas igniting systems, and more particularly to those controlled electrically from points remote from the burners.

The object of the invention is to provide means of the class set forth which although being very simple and thus comparatively inexpensive, will be highly efficient in operation and will possess a number of advantages.

With this general object in view, the invention resides in certain novel features of construction and in unique combinations of parts hereinafter fully described and claimed, and shown in the drawings wherein:

Figure 1 is a diagram showing the improved system; Figs. 2 and 3 are side elevations of portions of burners, showing the application thereto of one of the elements of the system; Fig. 4 is an enlarged vertical section through such element, and Figs. 5 and 6 are horizontal sections thereof as seen on the planes indicated by the lines 5—5 and 6—6 of Fig. 4.

In these drawings, (referring more particularly to Fig. 1) the numeral 1 indicates broadly a gas light of a common type to which gas is supplied by a pipe line 2, such line having therein an electrically opened and closed valve 3. Carried by the burner 1, is a jump spark gas igniting device 4 which is shown in detail in Figs. 2 to 6 and will be hereinafter fully described.

Disposed at a suitable point remote from the burner 1, is a plurality of batteries 5 shown in the present application as wired in series, while disposed adjacent said batteries is a jump spark coil 6. Connecting one terminal 7 of the primary coil 8 of said coil 6 with one terminal 9 of the batteries, is a wire 10, while leading from the other terminal of said primary coil is a wire 11 which is electrically connected with a switch tongue 12 normally spaced from but to be

forced into contact with the platinum point or the like on an additional and parallel switch tongue 13. From the tongue 13, a wire 14 leads to the other terminal 15 of the batteries, whereby when the switch tongues 12 and 13 are brought into contact, the circuit of the primary coil 8 will be completed.

Leading from the terminal 7 to one terminal of the secondary coil 16 of the jump spark coil, is a shunt 17, while the induced current is led from said coil 16 through a wire 18, to a third switch tongue 19 into contact with which a fourth tongue 20 is adapted to be brought upon actuation of the tongue 12, an insulating block 21 being provided on said tongue 12 for contact with the tongue 20 to operate the latter. Leading from the tongue 20, is a wire 22 which is electrically connected with a wire 23 carried by the device 4 and having its end bent 70 toward the end of the pipe line 2 immediately above the mantle or other type of burner proper with which the burner 1 is equipped.

When the switch tongues 12 and 13, and 19 and 20, are brought into contact, not only the primary circuit of the coil 6 is completed, but the secondary current passes therefrom to the wire 23, such current then leaping the gap between said wire and the pipe 2 to form a spark, and finally returning to the batteries through the pipe line 2 and a wire 24 which is grounded thereto and is connected electrically with the wire 14. Simultaneously with the completion of the circuits for causing an electric spark adjacent the burner proper, the valve 3 is opened, said valve being wired as follows. Independent of the batteries 5, is an additional battery 25 from one terminal 26 of which a wire 27 leads to a switch tongue 28 disposed parallel to but spaced from the tongue 12, both of these tongues having their free ends curved inwardly and then outwardly as disclosed at 29 and receiving therebetween an insulating cone 30 on a stem 31, the latter having a push button 32. Thus, when the push button is actuated, the tongue 12 is forced outwardly to close the switches of the primary and secondary circuits of the jump spark coil 6, while the tongue 28 is forced toward an additional tongue 33 to overcome the gap existing between the two. Leading from the tongue 33, is a wire 34, said wire being connected

100

105

110

to a magnet, solenoid or the like, with which the valve 3 is provided, such magnet, solenoid or the like, being in turn grounded by a wire 35 to the pipe 2, whereby when 5 the switch tongue 28 is forced toward the tongue 33, the current will flow from the terminal 26 of the battery 25, through the wire 27, through said switch tongues, and through the wire 34, to the valve 3, from 10 this valve through the wire 35 to the pipe 2, from the latter through the wire 24 to the wire 14, and will then return from the latter to the other terminal 36 of the battery 25 through a branch wire 37. The current 15 in so traveling, opens the valve 3, and since the switches of the primary and secondary coils 8 and 6 are completed at the same time, an electric spark will jump across the gap between the wire 23 and pipe 2, thereby igniting the burner. Needless to say, in order to complete the circuits above 20 described, it is simply necessary to depress the single push button 32, and when sufficient time has elapsed to allow the gas to 25 be ignited, releasing of the button 32 will open the switches of the circuits including the jump spark coil, and will likewise break the circuit used to open the valve 3. The latter, however, remains open until closed 30 by electrical means now to be described. Spaced from the plunger 31 is an additional plunger 38 having a push button 39 at its outer end and a cone 40 at its inner end, such cone being formed of insulating 35 material and disposed in contact with the laterally bent end 41 of a switch tongue 42, whereby to force the latter toward an additional tongue 43. Leading from the wire 40 27 to the tongue 43, is a current conducting wire 44, while continuing from the tongue 42 is an additional wire 45, the latter being so connected with the valve 3, as to cause the latter to be closed when the button 39 45 is operated and current flows from the battery 25 through the wire 27, switch tongues 42 and 43, and wire 45, to the valve 3 and from said valve through the pipe 2 and wires 24, 14, and 37, back to the battery. Thus it will be evident that the burner may 50 be extinguished at will from a remote point.

The preceding description refers primarily to Fig. 1 of the drawings, but the details of the igniting device 4 are shown more particularly in Figs. 2 to 6. In Fig. 2, a burner 46 is shown of the type commonly known as the "Millar-burner", such burners being provided with a substantially dome-shaped cover plate 47 having at one side a horizontally disposed flat surface which constitutes a seat 48, while at the center of this seat a circular opening is provided. Depending through this opening, is the lower end of the upright cylindrical body 49 of the device 4. The cylindrical body 49 is

provided with an annular outstanding shoulder 50 which is formed integrally with its intermediate portion and which is adapted to bear against the seat 48 of the burner 46, or against a similar seat 48^a of the Welsbach burner or the like 46^a (see Fig. 3) or, if the type of light shown in Fig. 1 is provided, the shoulder in question will rest upon a suitable horizontally disposed surface surrounding an appropriate opening through which the lower end of the body 49 projects. 75

The body 49 is provided throughout its length with a cylindrical passage 51 whose upper end is enlarged as disclosed at 52 and receives therein a tubular internally threaded binding post 53. Secured in any appropriate manner within the lower end of the post 52, is the upper end of the wire 23, the latter being extended from said binding post through the passage 51 and beyond the lower end of the body 49. The uninsulated end of the wire 22 is inserted into the upper end of the tubular binding post 53, and a wedge or the like 54 is driven into said post to bind the wire therein as clearly disclosed in Fig. 4, after which a cap member 55 is correctly positioned upon the upper end of the body 49, to reliably insulate the exposed portions of the wedge 54 and wire 22, said cap member including a head having therein a central opening through which the parts just mentioned project, and an annular flange which depends from said head and snugly surrounds the upper end of the body 49, such end being preferably though not necessarily increased in diameter. 95

By constructing the device 4 in the manner set forth in the preceding description, it will be evident that although its construction is very simple and inexpensive, its operation will be efficient. Needless to say, the projecting lower end of the wire 23 may be bent laterally at numerous angles for accommodating the device to application upon burners of numerous types and if found necessary, said end may be totally or partially removed according to requirements. 105

The foregoing description, when taken in connection with the accompanying drawings, is thought to be sufficient to familiarize those skilled in the art to which the invention relates, with the uses, advantages, and utility of the construction provided. Further description is therefore deemed superfluous. It may be well, however, to add that although the system is shown and described for electrically igniting gas burners, it might well be applied to use in connection with burners using liquid fuel, and to more emphatically explain the functions of using switches in both the primary and secondary circuits and for using two batteries. 115 120 125

The first provision is made in order that any number of lights may be operated inde-

pendently of each other by using one set of batteries and one spark coil. If this provision were not made, a set of batteries and a spark coil for each lamp would be necessary.

5 The object of the separate battery for operating the electric valve, rather than using current from the main battery, is to protect such valve against high voltage.

I claim as my invention:

- 10 1. The combination with a burner, a pipe line for supplying fuel thereto, an electrically opened valve in said pipe line, and a jump spark device adjacent the burner; of an electric circuit including the jump spark device, a jump spark coil in said circuit, an additional circuit including the electrically opened valve, switch means for completing the two circuits, and a single manually operable member for closing said switch means
- 15 20 at a single operation.
- 20 2. The combination with a burner, a pipe line for supplying fuel thereto, an electrically opened valve in said pipe line, and a jump spark device adjacent the burner; of a source of current, a circuit including said source and the jump spark device, a jump spark coil likewise included in said circuit, an additional source of current, an additional circuit including said additional source and the electrically opened valve, independent switches for the two circuits, and a single push button for simultaneously closing both switches.
- 30 3. An ignition device of the class described

comprising an upright elongated one-piece 35 cylindrical body having a rectilinear bore formed throughout its length, said bore having a cylindrical enlargement opening through the upper end of the body, a tubular internally threaded binding post received 40 snugly in said enlargement and projecting above the body, a wire confined snugly in the bore and having its upper end secured in the lower end of the tubular binding post, the lower end of said wire being extended 45 below the body, a current conducting wire received in the tubular internally threaded binding post and rising therefrom, a wedge driven downwardly in the binding post and forcing the wire into tight biting engagement with the threads therein, said wedge having a lateral projection above the post to render it easily removable, and a tubular cap fitting over the upper end of the body and having an opening receiving therein the projecting upper ends of the binding post and wedge whereby to normally conceal them from view, said cap, however, being slideable vertically from the body to render the wedge accessible for the purpose of removing the same.

In testimony whereof I have hereunto set my hand in presence of two subscribing witnesses.

WILLIAM LOWMAN.
